COMBINATION SELECTOR

William Parkerson, New Orleans, La., assignor of
one-half to E. Chandler Ricker, Dallas, Tex.

Application August 28, 1934, Serial No. 741,864

10 Claims.

(Cl. 40—70)

This invention relates to combination selectors and more particularly to combination selectors embodying a construction and arrangement of parts capable of producing a maximum number 5 of different combinations from a given number of items available for combining. Selectors constructed and arranged in accordance with my invention are adapted for the setting up of various different kinds of combinations, for example, 10 varying combinations of foods for changing menus from day to day, or varying combinations of letters, words, figures, symbols, pictures, or the like, for the instruction of students in "sight" work, mental arithmetic, memory work or the 15 like.

It is well known that the provision of a varied diet presents a rather vexatious problem to housewives and restaurant operators and that patrons of restaurants often find it difficult to 20 decide upon what foods they desire to select from the frequently lengthy list on the conventional menu card. A selector in accordance with my invention is particularly well suited for assisting such persons in the selection of varying food 25 combinations and accordingly my invention will be described as embodied in a menu selector, although it is obvious that selectors embodying the invention may be employed for other combination selection purposes.

An object of my invention is to provide a combination selector so constructed and arranged as to be capable of setting up all possible combinations available from a plurality of groups of items, taking one item at a time from each group, 35 i. e., each combination comprising a plurality of items each of which is a selected one from its own particular group, all of the combinations possible being exhausted before recurrence of any combination.

Generally stated my invention consists in the provision of a selector device including a plurality of rotatable elements each bearing indicia arranged to register with or be displayed through openings in a cover, and common driving means 45 for the rotatable elements having independent driving connection with each, the arrangement being such that step-by-step operation of the driving means will cause step-by-step changes in the combinations displayed through the openings, all possible combinations being exhausted before the combination originally displayed recurs. In the preferred form, the rotatable elements referred to comprise toothed wheels, the 50 numbers of the teeth in the wheels being prime to

each other, that is the numbers of the teeth in the wheels have no exact common divisor.

The invention will be understood from the following detailed description of preferred embodiments thereof, the appended claims, and the accompanying drawings, in which:

Figure 1 is a top plan view of one form of selector embodying the invention;

Figure 2 is a top plan view of the form shown in Figure 1 but with the top cover plate removed;

Figure 3 is a section on the line 3—3 of Figure 1;

Figure 4 is a top plan view of a modification;

Figure 5 is a top plan view of the modification with the top cover removed; and

Figure 6 is a section on the line 6—6 of Figure 4.

The menu selector shown for the purpose of illustration in Figures 1, 2 and 3 includes a top cover plate A provided with a plurality of spaced combination or food-designating openings 1, 2, 3, 4, 5 and 6 and an index or "day" opening 7, a bottom cover plate B mounted on a pintle 8 for rotation in a plane parallel to the plane of the top cover plate, and an assembly C of rotatable selector elements associated respectively with the openings 1, 2, etc. A hole 9 may be provided in the front cover plate to permit hanging the device on a hook or the like.

The bottom cover plate bears the names of days of the week in circumferentially spaced areas indicated at 10, 11, 12, 13, 14, 15, 16 and these names are adapted to register with the day opening 7 when the bottom cover plate is rotated relatively to the top plate A.

Each of the openings 1, 2, 3, 4, 5, and 6 bears a caption corresponding to the class or kind of food items to be displayed through the opening, for example, the opening 1 is captioned "Main dish" indicating that the item of food constituting the meat or other main dish forming part of a menu combination will be displayed through this opening. Similarly, the opening 2 is captioned "Salad", the opening 3 "Green vegetable", the opening 4 "Soup", the opening 5 "Starchy vegetable", and the opening 6 "Dessert".

The selector assembly C comprises a plurality of toothed gear wheels 1^a, 2^a, 3^a, 4^a, 5^a and 6^a associated respectively with the openings 1, 2, 3, 4, 5 and 6 and mounted for rotation on pintles 1^b, 2^b, 3^b, 4^b, 5^b, and 6^b, respectively. Each wheel bears spaced items of printed, lithographed or embossed matter, each item being the name of a specific food of a given class. Thus, the wheel 1^a bears the names "Beef", "Turkey", "Pork" and

the names of any other desired meats or the like, these names being so located as to be displayed through the "Main dish" opening 1 when the wheel 1^a is rotated. Similarly the wheel 2^a bears the names of salads, including for example, "Fruit", "Lettuce" and "Tomato", these names being adapted to register with the "Salad" opening 2 when the wheel 2^a is rotated. The wheels 3^a, 4^a, 5^a and 6^a correspondingly bear the names of specific foods coming under the food class designations captioning the openings 3, 4, 5 and 6.

It will be understood that the names of the foods appearing in the cover plate openings for any particular setting of the wheels designates what the complete dinner menu shall be. A feature of the present invention resides in the provision of means for driving the wheels in step-by-step increments so as to exhaust all possible menu combinations consisting of one each of the different food classes before reverting to the combination started with. In the attainment of this end, I provide common driving means which, in the form shown in Figures 1, 2 and 3, comprises a central driving gear 17 secured to the bottom cover plate B and meshing independently with each of the wheels 1^a, etc., and provide the wheels 1^a, 2^a, 3^a, 4^a, 5^a and 6^a with teeth the numbers of which are prime to each other. For example, in the form shown, the wheel 1^a has 19 teeth, the wheel 2^a has 16 teeth, the wheel 3^a has 15 teeth, the wheel 4^a has 11 teeth, the wheel 5^a has 13 teeth, and the wheel 6^a has 17 teeth. The driving wheel 17 has 7 teeth.

In operation, the top cover plate is held stationary and the bottom plate B is rotated in a clockwise direction so as to advance the "Day" reading say from Monday to Tuesday. This will move each of the food designating wheels 1^a, 2^a, etc., so as to provide a new menu combination. By reason of the novel construction and arrangement of parts, if the bottom plate be moved to advance one space each day, then:

1. No dish will recur on the same day of the week more often than once in about eleven weeks.
2. No two dishes will recur together more often than once in about four months.
3. No three dishes will recur together more often than once in about six years.
4. The precisely identical menu will not recur more often than once in thirty thousand years.

The selector provides exactly 11,085,360 different available menu combinations.

Obviously, no one could use all the different combinations thus available, but nevertheless the great number of combinations possible constitutes a desirable advantage, since the user may, if desired, keep advancing the bottom plate B until a combination is presented which appeals to the particular individual user.

The selector device shown in Figures 1, 2 and 3 may be constructed of any kind of sheet material which preferably should be thin and light and may even be relatively flexible, such as card board. When using flexible material, it may be advisable to provide a retaining flange or disc 18 secured to the driving wheel 17 and extending in front of the wheels 1^a, 2^a, etc. The flexibility of the wheels 1^a, 2^a, etc., permits them to overlap, yet to lie relatively close to the cover plate A on which they are mounted, thus providing a thin, compact assembly.

Referring now to the modification illustrated in Figures 4, 5 and 6, there is shown a selector including a top cover plate D, a bottom cover

plate E connected to the plate D by means of studs 20, and a selector wheel assembly F mounted between the cover plates.

The plate D is formed with food designating openings 21, 22, 23, 24 and 25 captioned "Drink", "Vegetable", "Meat", "Salad" and "Dessert", respectively.

The selector wheel assembly F comprises toothed wheels 21^a, 22^a, 23^a, 24^a and 25^a associated respectively with the openings 21, 22, etc., and each bearing the names of specific foods coming under the associated class designations. The wheels are of different diameters and are positioned in mutually superposed relation in parallel planes so that their axes (extended) all intersect a straight line lying in a plane parallel to the planes containing the wheels and so that the bottoms of their pitch circles (as viewed in the drawings) all lie on a straight line normal to the cover plates, thus enabling the larger wheels, which are on the bottom, to be partially exposed in order to permit the food names on all the wheels to be visible through the openings. The wheels are mounted in this arrangement by means of a bearing element 26 of zig-zag shape 25 and comprising pintle portions 21^b, 22^b, 23^b, 24^b and 25^b and connecting portions 26^b.

A common driving wheel or gear 27 has independent driving connection with each of the wheels 21^a, 22^a, etc., and is adapted to be rotated by means of a knurled knob 28. In this form also, the selector wheels preferably have numbers of teeth which are prime to each other.

As previously stated, my improved combination selector is capable of various uses in addition to those set forth herein, by way of example, in explaining the principles of novel construction and arrangement of parts; and it will be understood that various changes may be made in the specific construction and arrangement of the parts without departing from the invention as defined in the claims.

I claim:

1. In a device of the character described, the combination of a cover provided with a plurality of openings; a plurality of toothed driven wheels mounted under said cover and associated respectively with said openings, there being spaced printed matter items on said toothed driven wheels adapted to register with the respective associated openings upon rotation of said wheels; and a toothed driving wheel independently connected to the respective driven wheels; the numbers of the teeth in the driven wheels being prime to each other.

2. In a device of the character described, the combination of a top cover plate provided with a plurality of openings; a plurality of toothed driven wheels mounted under said cover plate and associated respectively with said openings, pintles carried by the cover plate and journaling the respective wheels for rotation, said wheels each bearing spaced printed matter items adapted to register with the respective associated openings upon rotation of said wheels; a bottom cover plate mounted for rotation in a plane parallel to the plane of the top cover plate; and a toothed driving gear secured to and rotatable with said bottom cover plate and having independent driving connection to each of said driven wheels.

3. In a device of the character described, the combination of a top cover plate provided with a plurality of openings; a plurality of toothed driven wheels mounted under said cover plate and associated respectively with said openings, pintles

carried by the cover plate and journaling the respective wheels for rotation, said wheels each bearing spaced printed matter items adapted to register with the respective associated openings upon rotation of said wheels; a bottom cover plate mounted for rotation in a plane parallel to the plane of the top cover plate; and a toothed driving gear secured to and rotatable with said bottom cover plate and having independent driving connection to each of said driven wheels, the numbers of teeth in said driven wheels being prime to each other.

4. In a device of the character described, the combination of a top cover plate provided with a plurality of openings spaced substantially around the center of the plate; a plurality of flexible toothed driven gears under said cover plate and bearing spaced printed matter items; pintles carried by said cover plate and mounting said gears for rotation in association with the respective openings to display said printed matter items therethrough; a bottom cover plate connected to said top cover plate; a toothed driving gear between said top and bottom cover plates and journalled for rotation about an axis located substantially centrally with respect to said pintles, said driven gears each meshing with said driving gear and certain of the driven gears overlapping each other, the flexibility of said driven gears permitting them to overlap while the non-overlapping portions lie close to said top cover plate.

5. In a device of the character described, the combination of a top cover plate provided with a plurality of openings spaced substantially around the center of the plate; a plurality of flexible toothed driven gears under said cover plate and bearing spaced printed matter items; pintles carried by said cover plate and mounting said gears for rotation in association with the respective openings to display said printed matter items therethrough; a bottom cover plate journalled for rotation relative to said top cover plate and about an axis passing substantially centrally with respect to said pintles; a driving gear secured to said bottom cover plate and rotatable therewith and meshing independently with said driven gears; and a flange on the top of said driving gear extending partially over the top sides of said driven gears.

6. In a device of the character described, the combination of a top cover plate provided with a plurality of openings spaced substantially around the center of the plate; a plurality of flexible toothed driven gears under said cover plate and bearing spaced printed matter items; pintles carried by said cover plate and mounting said gears for rotation in association with the respective openings to display said printed matter items therethrough; a bottom cover plate journalled for rotation relative to said top cover plate and about an axis passing substantially centrally with respect to said pintles; a driving gear secured to said bottom cover plate and rotatable therewith

and meshing independently with said driven gears, the numbers of teeth in said driven gears being prime to each other; and a flange on the top of said driving gear extending partially over the top sides of said driven gears.

5

7. In a device of the character described, the combination of a cover plate provided with a plurality of openings; a plurality of rotatable driven elements of different diameters disposed in mutually superposed relation in parallel planes under said cover plate and having spaced items of printed matter thereon adapted to register with the respective openings upon being rotated; bearing means mounting said driven elements for rotation with the individual axes of rotation all intersecting a straight line lying in a plane parallel to the planes containing said rotatable driven elements and with the pitch diameters of said elements lying substantially in one straight line normal to said cover plate; and a rotatable common driving means having independent driving connection with each of said driven elements.

8. A device as set forth in claim 7 in which the rotatable driven elements and the common driving means comprise toothed gears, the numbers of teeth in the driven gears being prime to each other.

9. In a menu selector, the combination of a cover provided with a plurality of food class openings and with a "Day" opening; a plurality of rotatable food designating toothed wheels associated respectively with the food class openings and each bearing a plurality of names of foods of a given class adapted to register with the associated food class opening upon the element's being rotated; a rotatable day designating element bearing the names of the days of the week adapted to register with said "Day" opening upon rotation of said day designating element; and common driving means for effecting rotation of said food class designating elements and being connected to said day designating element, the common driving means comprising a toothed wheel having independent driving connection with each of said food designating toothed wheels, the numbers of the teeth in the food designating toothed wheels being prime to each other.

10. In a device of the character described, the combination of a cover provided with a plurality of combination openings and with an index opening; a plurality of rotatable toothed combination wheels associated respectively with the combination openings and each bearing a plurality of printed items adapted to register with the associated combination openings upon rotation of said wheels; a rotatable index wheel bearing indicia adapted to register with said index opening upon rotation of the index wheel; and common driving means having independent driving connection with said wheels, the numbers of the teeth in said combination wheels being prime to each other.
